(21) Appl. No.: **29/308,598**

(57) **CLAIM**

(22) Filed: **Jun. 24, 2008**

The ornamental design for a decorative bookworm head for an interconnectable seating array, as shown and described.

(51) **LOC (9) Cl.** 06-01

DESCRIPTION

(52) **U.S. Cl.** D6/359

FIG. 1 is a front view of my design.

(58) **Field of Classification Search** D6/359,

FIG. 2 is a rear view of my design.

D6/358, 334, 345, 351; 297/181; D21/415

FIG. 3 is a top view of my design.

See application file for complete search history.

FIG. 4 is a bottom view of my design. The broken lines in FIG. 4 are included for the purpose of illustrating a portion of the environmental structure that forms no part of the claimed design.

(56) **References Cited**

FIG. 5 is a left side view of my design; and,
FIG. 6 is a right side view of my design.
